REFRIGERATOR CAR CONSTRUCTION

Charles D. Bonsall, Pittsburgh, Pa., assignor to
Standard Railway Devices Company, a corpora-
tion of Delaware

Application April 24, 1939, Serial No. 269,697

10 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling or heating means depending upon the prevailing outside temperature.

This invention applies particularly to cars in which the cooling means, preferably containers for water ice, eutectic ice, brine or dry ice, are suspended immediately below the ceiling of the car. The lading is supported in spaced relation to the floor by a foraminous rack. Flues, preferably associated with the side walls of the car, communicate between the refrigerant compartment and the space under the floor rack to provide a path for the circulation of air. The path is from the refrigerant compartment downwardly through the aforementioned flues, through the space under the floor rack, and upwardly through the lading compartment to the refrigerant compartment.

An object of this invention is to firmly support the refrigerant containers within the car. The refrigerant carried in the containers commonly weighs several tons and the containers must therefore be securely mounted, particularly when it is considered that the refrigerant or the containers falling upon the lading would result in the virtual destruction thereof with consequent high damage claims upon the operator of the car.

Another object of the invention is to provide refrigerant containers of maximum capacity and, further, to provide increased capacity without increased height. I accomplish this by building the containers with greater width and length and shaping the walls to conform to the contour of the inside walls of the car.

It is another object of the invention to stiffen the bottom of the refrigerant container to prevent extensive sagging thereof under the load imposed by the refrigerant. This is accomplished partly by securing to the bottom of the container upstanding ribs and partly by supporting the container bottom from the roof structure of the car by means of the aforementioned upstanding ribs.

A further object is to utilize the aforementioned upstanding ribs as a means to retard surging of the refrigerant within the container due to service movements of the car.

Other objects and advantages of my invention will be apparent from the following detailed description by referring to the accompanying drawings.

In the drawings:

Fig. 1 is a transverse section of a refrigerator car embodying my invention, the left half being

on line 1L—1L and the right half on line 1R—1R of Fig. 2.

Fig. 2 is a longitudinal section line 2—2 of Fig. 1.

Fig. 3 is a section on line 3—3 of Fig. 2.

Fig. 4 is a view similar to a portion of Fig. 2 showing a modified construction.

Fig. 5 is a view similar to a portion of Fig. 1 showing a modified construction.

The general parts of the refrigerator car shown are roof 2, side walls 3, floor 4, hatch 5, refrigerant container 6, lading compartment 7, side wall flues 8, floor rack 9 and space 10.

The side wall 3 comprises inner (20) and outer (21) side plates and inner (23) and outer (24) side sills. Inner (26) and outer (27) posts extend between and are secured to the inner side plate 20 and side sill 23 and outer side plate 21 and side sill 24 respectively. The outer sheathing 28 is secured to the outer structural members and the inner sheet member 30 and inner lining 31 are secured to the inner structural members, the member 30 having formed therein a panel 33 which is spaced from the lining 31 to form the flue 8.

The inner side plates 20 preferably comprise Z-bars with the webs 37 thereof substantially horizontal and the upstanding leg 38 disposed outwardly of the depending leg 39. The container 6 preferably extends between the side plates 20 and has the walls 42 adjacent thereto formed with the upper portions 43 offset outwardly of the lower portions 44. The upper (43) and lower (44) portions of the walls 42 are connected by the webs 46 which substantially conform in slope to the webs 37 of the inner side plates 20 and rest thereon, thereby supporting the container 6.

Spaced apart carlines 50 are formed of inverted channels having webs 51 and depending flanges 52. The walls 54 adjacent the carlines 50 are formed with the upper portions 55 thereof offset outwardly from the lower portions 57 and connected thereto by the substantially horizontal webs 58. The slope of the webs 58 conforms substantially to the slope of the carline webs 51 upon which the container webs 58 rest for the purpose of supporting the container 6. The carlines 50 extend between and are secured to the inner side plates 20 by a means such as the welds 60 (Fig. 3). The tops 62 of the containers 6 support the roof insulation 63, bridge pieces 64 being arranged to support the insulation 63 between the containers 6. The bridge pieces 64 are preferably secured to the carlines 50 by the bolts 65.

Spaced apart clips 70 are secured to the depending flanges 52 of the carlines 50. Nailing strips 71 are secured to the clips 70 by the bolts 72 and the partition 73 is secured to the strips 71, preferably by nailing. Drip pans 75 rest upon the partition 73 with the ends 76 thereof offset

upwardly and over the nailing strips 71. The partition 73 is spaced from the bottom of the container 6 to form a duct 78 which communicates with the flue 8.

Upstanding baffles 85 having oppositely disposed feet 86 are secured to the bottom of the container 6 to retard surging of the refrigerant due to service movements of the car. Restraining members 87 are secured to the baffles 85. Gusset members 88 are interposed between the upstanding marginal flanges 90 of adjacent roof sheets 92, the gusset members 88 being secured to the flanges 90 and to the inverted channel shaped carlines 93 which straddle the flanges 90. Insulation 96 is interposed between the gusset members 88 and restraining members 87.

An opening 101 is provided by spacing apart the partitions 73 on opposite sides of the car, the opening 101 serving to conduct air from the lading compartment 7 to the ducts 78. An insulating member 102, such as wood, is attached to the bottom of the container 6 above the opening 101 to prevent the formation of condensate upon the container, which condensate would be liable to drip upon the lading with consequent damage thereto.

Fig. 4 shows a modification in which the carline 110 is provided with outwardly projecting reflanges 111 upon which the bottoms 113 of the containers 6 rest. The walls 54 of the containers 6 are also formed with the upper portions 55 thereof offset outwardly from the lower portions 57 and connected thereto by webs 58 which rest upon the webs 51 of the carlines 110.

Fig. 5 shows a modification in which the inner side plate 120 has an upstanding leg 121 and a depending leg 123 connected by an inclined web 124. The refrigerant container has the wall 42 formed with the upper portion 126 offset outwardly from the lower portion 127, said upper and lower portions being connected by an inclined web 128 which rests upon the web 124 of the side plate 120, thereby supporting the container 6.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a roof supported by an external carline and a refrigerant container below said roof, an upstanding baffle secured to the bottom of said container substantially below said carline to retard surging of liquid in said container, a member secured at the lower end thereof to said baffle, means to secure the upper end of said member to said carline, and means to insulate said member from said carline.

2. In a refrigerator car having a roof supported by a carline and a refrigerant container below said roof, an upstanding baffle secured to the bottom of said container to retard surging of liquid in said container, and means to secure said baffle to said carline.

3. In a refrigerator car having a roof supported by a carline, a refrigerant container below said roof, means to prevent sagging of the container bottom comprising a member depending from

said carline, and means to secure said member to said bottom.

4. In a refrigerator car having a wall comprising a plurality of spaced apart substantially vertical posts, a side plate extending between and secured to the upper parts of said posts, said side plate having a laterally extending surface, a refrigerant container adjacent said car wall, a wall of said container having an upper portion offset outwardly from a lower portion and connected thereto by a web arranged to rest upon said laterally extending surface to provide a support for said container.

5. In a refrigerator car having a wall comprising a plurality of spaced apart substantially vertical posts, a side plate extending between and secured to the upper parts of said posts, said side plate having a substantially horizontal surface, a refrigerant container adjacent said car wall, a wall of said container being formed with a substantially horizontal web arranged to rest upon said horizontal surface to provide a support for said container.

6. In a refrigerator having a frame member having a pair of laterally extending surfaces, one spaced outwardly of and below the other, a refrigerant container having the upper portion of one of the walls thereof offset outwardly from the lower portion thereof, said upper and lower portions being connected by a web arranged to rest upon the upper of said surfaces, the bottom of said container arranged to rest upon the lower of said surfaces.

7. In a refrigerator having spaced apart walls and a carline extending therebetween and secured thereto, said carline having a laterally extending surface, a refrigerant container having the upper portion of one of the walls thereof offset outwardly from the lower portion thereof, said upper and lower portions being connected by a web arranged to rest upon said surface to provide a support for said container.

8. In a refrigerator car having a wall comprising a plurality of spaced apart substantially vertical posts, a side plate extending between and secured to the upper parts of said posts, said side plate comprising an angular member with one leg thereof substantially horizontal, a refrigerant container adjacent said car wall, a wall of said container being formed with a substantially horizontal web arranged to rest upon said leg to provide a support for said container.

9. In a refrigerator car having a wall comprising a plurality of spaced apart substantially vertical posts, a side plate extending between and secured to the upper parts of said posts, said side plate having a substantially horizontal surface, a refrigerant container adjacent said car wall, a wall of said container being formed with a substantially horizontal web arranged to rest upon said horizontal surface to provide a support for said container.

10. In a refrigerator having a side plate comprising a Z-bar with the web substantially horizontal, a refrigerant container having the upper portion of one of the walls thereof offset outwardly from the lower portion thereof, said upper and lower portions being connected by a substantially horizontal web which rests upon the web of said Z-bar.

CHARLES D. BONSALL,
